UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

CONDUCTOR SUPPORT.

1,405,609.

Specification of Letters Patent. Patented Feb. 7, 1922.

Application filed September 3, 1921. Serial No. 498,227.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Con-
ductor Supports, of which the following is a
specification.

My invention relates to conductor supports
10 and particularly to that class of device for
supporting a trolley conductor from a cat-
enary cable, hanger, bracket, etc., as is now
common practice.

The object of my invention is to provide a
15 device by means of which the conductor may
be gripped by a pair of clamping jaws, and
the jaws locked in clamping relation to the
conductor.

In the drawing accompanying this specifi-
20 cation—

Fig. 1 shows a side view of my invention
in partial section.

Fig. 2 shows an end view in section.

Fig. 3 shows a view of Fig. 1 on line 3—3
25 in section.

Fig. 4 shows a view of Fig. 2 on line 4—4
in section.

In the preferred form of my device I use
a pair of duplicate clamping members 1—1
30 each provided with a jaw 2 to grip the con-
ductor. The upper portion of the two clamp-
ing members when in position form a hollow
truncated portion 3 of rectangular shaped
35 sides surmounted by a flange 3' and a pro-
jecting collar 4. Projecting from the exte-
rior of the parts 3 and 4 are wings 5 oppo-
sitely disposed and in line with the axis of
the jaws 2 and projecting from each wing
is a projection 6.

40 A hollow truncated cap 7 is mounted on
the truncated portion 3 of the clamping
members and is provided with recesses 8 to
receive the wings 5 and projections 6. To
the lower end of the recess wall a project-
45 ing lip 9 is formed (shown in dotted line) which
can be bent inward and upward (shown in
full lines) whereby a portion of the opening
at the lower end of the recess may be closed
thereby forming a shoulder for the projec-
50 tion 6 to rest upon when the parts are
relaxed and also prevents the disassembly
of the parts. A recess 10 is formed in the top
of the cap.

Within the hollow of the part 3 on the
55 clamping members is positioned a nut 11, in-

ternally threaded, and engaging the inner
adjacent walls of the clamping members to
prevent rotation thereof.

The above description covers the construc-
60 tion of my invention proper and the con-
struction described may be applied to the
various supports now commonly known to
the trade and while I show the device as
secured to a support for further attachment
65 to a catenary cable, it may also be secured to
other forms of support such as the well
known insulated bolt and hanger.

In attaching my device to a catenary cable
a rod 12 passes through the opening 10 and
is threaded into the nut 11. Mounted on the
rod 12 and in threaded engagement there-
with is a nut 13 by means of which the
clamping members 1 and cap 7 may be
moved towards each other thereby moving
the clamping members towards each other,
75 and when a conductor 14 is placed between
the jaws 2 and the nut 13 rotated, moving
towards the cap 7 sufficiently, the conductor
will be gripped by the jaws and held secure.
A reverse rotation of the nut will permit dis-
engaging the conductor from the jaws.

Having illustrated and described my in-
vention, what I claim and wish to secure by
Letters Patent is:—

1. A conductor clamp comprising a pair
85 of clamping members, jaws at one edge to
engage and grip a conductor, a truncated
portion on the clamping members adjacent
the opposite end from the jaws, a supporting
90 member positioned within the truncated por-
tion of the clamping members and engaging
the side walls thereof to prevent relative
rotation, and engaging means on the clamp-
ing members to support the clamping mem-
bers, means on the supporting member to
95 secure the clamp to a hanger, a truncated
cap mounted on the truncated portion of
the clamping members to move the clamping
members towards each other, and hanger
means coacting with the supporting means
100 and cap to move the clamping members into
engagement with the conductor.

2. A conductor clamp comprising a pair
of clamping members, jaws at one edge to
engage and grip a conductor, a truncated
portion on the clamping members adjacent
the opposite end from the jaws, a supporting
105 member positioned within the truncated
portion of the clamping members and en-
gaging the side walls thereof to prevent rela-

tive rotation, and engaging means on the clamping members to support the clamping members, means on the supporting member to secure the clamp to a hanger, a truncated cap mounted on the truncated portion of the clamping members to move the clamping members towards each other, hanger means coaxing with the supporting means and cap to move the clamping members into engagement with the conductor, and means on the cap engaging means on the clamping members to prevent their separation when not engaged on a conductor.

3. A conductor comprising a pair of clamping members each provided with converging sides and having jaws at the one edge to grip a conductor, a cap having converging sides to receive the converging sides on the clamping members, a supporting member positioned between the clamping members in non-rotatable relation thereto and provided with means to receive a hanger, and means on the cap and clamping members to interlock and prevent separation of the parts.

4. A conductor clamp comprising a pair of clamping members each provided with converging sides and having jaws at the one edge to grip a conductor, a cap having converging sides to receive the converging sides on the clamping members, a supporting member positioned between the clamping

members and provided with means to receive a hanger, means on the cap and clamping members to interlock and prevent separation of the parts, a hanger engaging the supporting member and means movably mounted on the hanger to engage the cap to move the clamping members into holding relation with the conductor.

5. A conductor clamp comprising a retaining member, a two-part clamping member mounted in the retaining member and movable transversely thereto to grip a conductor, a supporting member positioned in the two-part clamping member and non-rotatable relative thereto and provided with means to receive a hanger, and means on the two-part clamping member and the retaining member to prevent separation of the parts.

6. A conductor clamp comprising a retaining member, a two-part clamping member mounted in the retaining member and movable transversely of the retaining member to grip a conductor, a supporting member positioned between the parts of the clamping members and non-rotatable relative thereto and provided with means to engage a hanger and means on the retaining member to be bent over and acting to engage means on the clamping member to prevent separation of the parts.

In testimony whereof I affix my signature.
SAMUEL S. MATTHES.
